ABSTRACT: A container for deploying a self-inflating target from an aircraft comprising an elongate tubular casing for the target, a nose cap and a weighted tail portion which also serves as an air scoop. Upon release from the aircraft the weighted tail portion orients the container vertically. A valve positioned in the air scoop controls the amount of air entering the target to prevent target ejection and inflation until the falling container and target have decelerated to a safe opening speed.

SELF-INFLATING TARGET DEPLOYMENT CONTAINER

STATEMENT OF GOVERNMENT INTEREST

The invention described herein may be manufactured and used by or for the Government of the United States of America for governmental purposes without the payment of any royalties thereon or therefor.

CROSS REFERENCE TO RELATED APPLICATIONS

In a copending application, Ser. No. 801,524 filed Feb. 24, 1969, applicant discloses a self-inflating target of the type which may be housed within and deployed from the container of the present invention. While the target of the copending application is not part of the present invention, it has been illustrated in the drawings and mentioned in the description of the preferred embodiment primarily to add clarity and to assure full understanding of this invention.

BACKGROUND OF THE INVENTION

The present invention relates generally to containers and more particularly to containers for housing inflatable targets which are to be transported by and dropped from aircraft.

Prior art sea targets are usually heavy wood or steel barges which must be towed to the selected target areas by ship. Such methods of target delivery are slow and impose expensive personnel and equipment requirements. These requirements are obviated by the container of the present invention when used with a self-inflating sea target.

SUMMARY OF THE INVENTION

Briefly the present invention is directed to a device which renders a self-inflating target droppable from an aircraft traveling at a relatively high speed. It is a compact storage and launching container part of which may be an integral part of the deployed target. It comprises a tubular casing for storing the deflated target, a removable nose cap mounted on the front of the casing and a weighted air scoop positioned on the rear of the casing. The weight of the air scoop properly orients the container upon its release from the aircraft. An airflow control valve is mounted in the air scoop for limiting the amount of air entering the scoop until the device decelerates sufficiently to permit ejection and opening of the target without damage.

STATEMENT OF THE OBJECTS OF INVENTION

One object of the present invention is to provide a means of delivering an inflatable target from an aircraft to a selected point.

Another object is to provide a valve means incorporated within the delivery means for controlling the entry of air into the target.

A further object is to provide a target delivery means which is simple and inexpensive in construction yet reliable in operation.

Other objects, advantages, and novel features of the invention will become apparent from the following detailed description of the invention when considered in conjunction with the accompanying drawings.

BRIEF DESCRIPTION OF THE DRAWINGS

FIG. 1 is a side elevational view of the container with portions broken away.

FIG. 2 is a slightly enlarged view of the weighted air scoop shown in FIG. 1 but rotated on its longitudinal axis 90°.

FIG. 3 is a rear end view of the container taken along line 3-3 of FIG. 2.

FIG. 4 (a-f) is a diagrammatic step-by-step illustration of the action of the container upon airdrop showing how the enclosed target is deployed.

DESCRIPTION OF THE PREFERRED EMBODIMENT

FIG. 1 of the drawings illustrates the circular target container 10 of the present invention which has a central elongate tubular packing barrel 12 with a detachable nose cap 14 mounted on the forward end and a weighted air scoop 16 located at its rear end. Reference is made to the aforementioned copending application for details of the target housed within the container.

10 The packing barrel 12 is the largest single section of the container 10 and provides the main storage area for the enclosed target. It is formed of two identical separable halves 18 and 20 the edges of which abut at 22 to form tubular packing barrel 12. The packing barrel is mated at the rear through lap joint 24 with the air scoop 16 and at the front through lap joint 26 with the nose cap 14. The latter is detachably located at the forward end of the packing barrel so that it can be pushed off by the emerging target and allow the barrel halves to separate after release of the container 10 from the aircraft.

20 The hollow air scoop 16 may be in the form of an annulus and is provided with a central aperture 27 through which air can pass into a target inflation sleeve 29 when the container is released from an aircraft. The air scoop may be formed of any suitable material such as sheet metal or plastic and has an outer surface 30 which is turned back upon itself in reentrant fashion to form an inner tubular sleeve 28 to which the target inflation sleeve 29 may be secured. An annular pocket 25 is formed at the juncture of sleeve 28 and ledge 30 and may accommodate a body of weighted material which may be lead and may be mounted in a plastic cement if desired. Such weight helps to vertically orient the container with the air scoop 16 in a forwardly or down position substantially coinciding with the trajectory path of its fall after release from an aircraft. Outer surface 30 may be mated to the end of packing barrel 12 through a suitable lap joint 24 as shown in FIG. 1.

An airflow control valve arrangement may be positioned in sleeve 28 and is adapted to limit the amount of air passing into the target so as to prevent premature target ejection. The 25 valve arrangement comprises a pair of flexible valve plates 34 hingedly mounted on a shaft 36 which is centrally and transversely mounted within the sleeve 28. Both valve plates 34 are normally held in an open position by springs 38 which connect each valve plate 34 to an opposed air scoop wall 40 substantially as shown in the drawings. An adjustable turnbuckle 39 may be interposed between wall 40 and each spring 38 for controlling the tension exerted on valve plate by such spring. Control of such tension permits varying the point at which the target is ejected and the container breaks up. A valve stop rod 35 42 extends transversely across sleeve 28 at a 90° angle to shaft 36 and is positioned behind the valve plates 34 in order to suitably position the plates in their closed position. Each valve plate is loosely fitted within the inner wall of sleeve 28 so as to effectively limit the amount of air flowing into the container when the valve plates are in the closed position. It will be apparent that if desired a suitable spring hinge may also be used to apply opening tension to the valve plates.

A pair of separable holding clamps 44 are positioned around the container 10 at the junctures of the packing barrel 12 with the nose cap 14 and the air scoop 16. The clamps function to hold the three parts of the container 10, i.e., nose cap 14, packing barrel 12 and air scoop 16 in their mated position and also serve as mounts for attachment of the container to a 50 conventional bomb rack. When the container 10 is released in the target area, the rings 44 come apart and the container will orient itself with the air scoop 16 directed forwardly along the path of trajectory due to its greater weight.

While in place on a bomb rack, the valve plates 34 are normally in the open position. Upon release the heavier rear end of the container causes it to swing around so that the air scoop faces forwardly along the trajectory path and the ram air pressure then acts upon the plates 34 to close them and prevent any air ingress into the scoop. However, as the container 55 decelerates to its terminal velocity the ram air pressure against

70 75 the valve plates 34 are normally in the open position. Upon release the heavier rear end of the container causes it to swing around so that the air scoop faces forwardly along the trajectory path and the ram air pressure then acts upon the plates 34 to close them and prevent any air ingress into the scoop. However, as the container decelerates to its terminal velocity the ram air pressure against

the valve plates is reduced and springs 38 can gradually force the plates open to allow ram air to enter the airscoop 16. This inflates the target which latter then forces off nose cap 14. Thereupon the packing barrel 12 splits into two halves 18 and 20. The inflatable target is now free from containment and the air entering the permanently attached airscoop 16 eventually completely fills out the descending target. Upon striking the ocean surface, the weighted airscoop 16 will sink thereby anchoring the target on the ocean surface.

I claim:

1. An air-droppable device for housing a target made of thin flexible material which target is adapted to be inflated by ram air forced thereinto when dropped through the earth's atmosphere comprising:

a container of elongate overall shape formed of a plurality of breakaway parts having interfitting edges;

a weighted airscoop positioned at the aft end of said container with an opening leading into the interior of said target; and

means for orienting the major axis of the container along the path of the container trajectory with the weighted airscoop directed forwardly when the container is dropped from a moving body; so that said container breaks up during its fall to free said target in order that it may become fully inflated before impact.

2. The device of claim 1 wherein the container comprises a nose section, a central body section and a tail section, said sections being interfitted together and forced off during the disas-

sembly.

3. The device of claim 1 wherein the airscoop is provided with airflow control means.

4. The device of claim 3 wherein the airflow control means automatically responds to ram air pressure so as to prevent air ingress during periods of high ram air pressure and to permit air ingress during periods of low ram air pressure.

5. The device of claim 4 wherein the airflow control means is adjustable to vary the point at which air ingress is permitted.

10 6. The method of erecting a collapsible target at a remote site comprising the steps of:

collapsing said target into a small bundle; encapsulating said bundle within a breakaway container, said container having a weighted airscoop positioned at the aft end thereof with an opening leading into the interior of said target;

transporting said container to a position above said site; releasing said container on a trajectory path directed

toward said site, whereupon the container will become oriented with the airscoop directed forwardly;

decelerating said container to its normal terminal velocity at free fall; and

20 25 decapsulated said collapsed target when such normal terminal velocity is reached, so that the collapsed target may fully expand to its normal shape before impact at the target site.
